UNITED STATES PATENT OFFICE

148,532

DESIGN FOR A HAND TRUCK OR SIMILAR ARTICLE

Frank E. Gaines, Alhambra, Calif.

Application September 20, 1946, Serial No. 133,467

Term of patent 14 years

(Cl. D14—3)

To all whom it may concern:

Be it known that I, Frank E. Gaines, a citizen of the United States, residing in Alhambra, in the county of Los Angeles, State of California, have invented a new, original, and ornamental Design for a Hand Truck or Similar Article, of which the following is a specification, reference being had to the accompanying drawings, forming a part thereof.

Figure 1 is a perspective view of a hand truck or similar article showing my new design.

Figure 2 is a side, elevational view of the hand truck in upright position.

Figure 3 is a top, end view of the hand truck taken in the direction of the arrow 3 of Figure 2.

Figure 4 is a bottom, end view of the hand truck taken in the direction of the arrow 4 of Figure 2.

Figure 5 is a bottom view taken in the direction of the arrow 5 of Figure 2.

Figure 6 is a plan view taken in the direction of the arrow 6 of Figure 2.

I claim:

The ornamental design for a hand truck or similar article, substantially as shown.

FRANK E. GAINES.
